RAILWAY TRAFFIC CONTROLLING
APPARATUS

Earl M. Allen, Edgewood, and Henry S. Young,
Wilkinsburg, Pa., assignors to The Union
Switch & Signal Company, Swissvale, Pa., a
corporation of Pennsylvania

Application March 14, 1935, Serial No. 11,130

6 Claims. (Cl. 246—219)

Our invention relates to railway traffic controlling apparatus of the type involving a railway traffic governing device controlled by a manually operable lever or other suitable device, subject to given traffic conditions.

One feature of our invention is the provision of a novel and improved arrangement for the control of a stick relay for requiring action by the leverman at the time the traffic governing device is operated. In respect to this feature, our invention is an improvement upon that disclosed in the co-pending application Serial No. 695,294, filed Oct. 26, 1933, by Earl M. Allen and Howard A. Thompson, for Interlocking control apparatus.

15 Our invention is also an improvement upon that disclosed in a copending application Serial No. 715,527, filed Mar. 14, 1934, by Ronald A. McCann, for Railway traffic controlling apparatus.

20 We will describe one form of apparatus embodying our invention, and will then point out the novel features thereof in claims.

The accompanying drawing is a diagrammatic view, showing one form of apparatus embodying our invention.

25 Referring to the drawing, the reference characters **1** and **1^a** designate the track rails of a stretch of railway track **Y** which is divided by insulated joints **2** into sections **B—C** and **C—D**. Each of these sections is provided with a track circuit, as shown for section **C—D**, comprising a battery, designated by the reference character **3**, connected across the rails adjacent one end of the section, and a relay, designated by the reference character **T**, connected across the rails adjacent the opposite end of the section.

30 Located in section **C—D** is a switch **H** for connecting track **Y** with a second track **Z**. Switch **H** is operated by a suitable mechanism designated by the reference character **M**.

40 At point **C**, signals **S^a** and **S^b** are shown for controlling eastbound traffic movements, that is, traffic movements from left to right, as shown in the drawing, over switch **H** in its normal and reverse positions, respectively.

45 Mechanism **M** is controlled by pole-changing contacts of a manually operable lever **k**, and by a lock relay **Q** and also by a stick relay **R**.

50 Lever **k** has a normal position **n** and a reverse position **r**. Pole-changing contacts **9** and **12** of lever **k** are closed when the lever is in the **n** and **r** positions, but are open when the lever is between these two positions. A third contact **6**, operated by lever **k**, is closed when the lever is between its **n** and **r** positions, but is open when 55 the lever is in either of these two positions.

Relay **Q** is controlled by an approach or stick locking relay **P** and by track relay **T**.

Locking relay **P** may be controlled in any suitable manner such, for example, as shown for relay **L** in a Patent No. 1,956,851, which was granted May 1, 1934, to C. A. Brooks and J. M. Pelikan, for Railway traffic controlling apparatus. The manner in which relay **P** is controlled prevents an operator from changing the position of switch **H** until a measured period of time has elapsed after a signal **S** has been caused to indicate stop, if an eastbound train has entered section **B—C** while one of the signals **S** is indicating caution or proceed.

5 Stick relay **R** is controlled by contact **6** of lever **k** and by lock relay **Q**. An asymmetric unit **i**, which may be of the well known copper oxide rectifier valve type, is connected across the terminals of relay **R** to permit current to flow in the direction indicated by the arrowhead portion of the symbol for unit **i** when relay **R** is disconnected from a source of energy.

As shown in the drawing, all parts of the apparatus are in the normal condition, that is, switch lever **k** is in its normal position **n**; switch **H** is in its normal position; signals **S** are indicating stop; relays **P**, **T** and **Q** are energized; and relay **R** is deenergized. The circuit by which relay **Q** is energized passes from terminal **x** of a suitable source of current not shown in the drawing, through contact **4** of relay **P**, contact **5** of relay **T**, and the winding of relay **Q** to terminal **o** of the same source of current.

We will assume that, with all parts of the apparatus thus in the normal condition, the leverman desires to reverse switch **H**. He will therefore move lever **k** to its reverse position **r**.

While lever **k** is between its **n** and **r** positions, a pickup circuit is closed for relay **R**, passing from terminal **x**, through contact **6** of lever **k**, contact **8** of relay **Q**, and the winding of relay **R** to terminal **o**. If contact **6** of lever **k** becomes opened before front contact **7** of relay **R** closes, the energy stored in relay **R** will be dissipated by current flowing through the path which includes asymmetric unit **i** and the winding of relay **R**, thereby tending to help relay **R** to close its front contacts **7** and **11**. Contact **7** of relay **R**, upon closing, completes a stick circuit for relay **R**, passing from terminal **x**, through contact **7** of relay **R**, contact **8** of relay **Q**, and the winding of relay **R** to terminal **o**. With this stick circuit closed, relay **R** will be retained in the energized condition after contact **6** of lever **k** opens when lever **k** reaches the **r** position.

With relay R energized, and with lever *k* in its *r* position, a reverse circuit will be completed for mechanism M, passing from terminal *x*, through contact 9 of lever *k* in its reverse position, mechanism M, contact 11 of relay R, contact 10 of relay Q, and contact 12 of lever *k* in its reverse position to terminal *o*. Mechanism M will now move switch H to its reverse position.

We will further assume that the leverman now 10 clears signal S^b for a train to move over switch H in the reverse position to track Z. Locking relay P will therefore be deenergized, permitting its contact 4 to open the circuit for relay Q. Relay Q, upon becoming deenergized, in turn permits its contact 8 to open, and thereby deenergize relay R. When the train enters section C—D, the circuit for relay Q will also be opened at contact 5 of relay T. As long as relay R remains deenergized, its contact 11 will be open in the circuit 20 previously traced for mechanism M.

When the leverman desires to return switch H to the normal position, he will return lever *k* to its *n* position, thereby energizing relay R, as previously described, when relay Q has again become energized. With relay R energized, and with lever *k* in its *n* position, a normal circuit will be completed for causing mechanism M to move switch H to its normal position. This normal circuit is the same as the reverse circuit previously 30 traced for mechanism M except that it includes contacts 9 and 12 of lever *k* in their normal positions instead of in their reverse positions.

We will now assume that, with all parts of the apparatus again returned to the normal condition, the leverman clears signal S^a, thereby deenergizing relay P, or that relay T becomes deenergized. With either relay P or T deenergized, relay Q will be deenergized, causing relay R to also be deenergized.

40 We will further assume that, while relay Q is deenergized, the leverman by mistake attempts to reverse switch H by moving lever *k* to the *r* position. On account of relay Q being deenergized, the pickup circuit for relay R will be open at contact 8 of relay Q, although it is closed at contact 6 of lever *k*. Since relay R therefore does not become energized, mechanism M will not become energized when lever *k* reaches the *r* position.

50 We will also assume that the leverman does not return lever *k* to its *n* position, and that while lever *k* is still in the *r* position, relay Q again becomes energized. Although the pickup circuit for relay R will now be closed at contact 8 of relay Q, it can not become closed at contact 6 of lever *k* without action at this time by the leverman to move lever *k* between its *n* and *r* positions to close contact 6 and thereby complete the pickup circuit for relay R.

60 From the foregoing description and the accompanying drawing, it follows that apparatus embodying our invention includes a stick relay which is so controlled as to require action by the leverman at a time when traffic conditions are suitable for operation of the switch. The stick relay will then remain energized as long as traffic conditions are suitable for operation of the switch. The circuit for the switch mechanism will therefore remain closed at contacts 10 and 11 as long 70 as conditions are suitable for operation of the switch. If traffic conditions becomes unsuitable for operation of the switch, any action by the leverman in order to be effective to operate the switch, must be taken after traffic conditions have again become suitable for operation of the switch.

Although we have herein shown and described only one form of railway traffic controlling apparatus embodying our invention, it is understood that various changes and modifications may be made therein within the scope of the appended claims without departing from the spirit and scope of our invention. 5

Having thus described our invention, what we claim is:

1. In combination, a stretch of railway track 10 including a switch, a manually operable switch lever having a normal and a reverse position and having a normal and a reverse contact closed only when said lever is in said normal and reverse positions respectively as well as having a 15 middle contact closed only when said lever is between its normal and reverse positions, a stick relay, a pickup circuit for said stick relay controlled by said middle contact and by traffic conditions in said stretch of track, a stick circuit for 20 said stick relay controlled by traffic conditions in said stretch of track independently of said lever, and means controlled by said normal and reverse contacts and by said stick relay for operating said switch to its normal and reverse positions 25 if said stick relay is energized.

2. In combination, a railway track switch, a manually operable switch lever having a normal and a reverse position, a traffic contact controlled by traffic conditions and arranged to be closed 30 only when said traffic conditions are suitable for said switch to be operated, a stick relay, a pick-up circuit for said stick relay closed by said lever when said lever is between its normal and reverse positions if said traffic contact is closed, a 35 stick circuit for said stick relay controlled by said traffic contact independently of said lever, and means controlled by said lever in its normal and reverse positions for operating said switch to its normal and reverse positions respectively if 40 said stick relay is energized.

3. In combination, a railway track switch, a manually controllable contact, a traffic contact closed only by traffic conditions suitable for operation of said switch, a stick relay, a pickup circuit for said stick relay closed by said manually 45 controllable contact if said traffic contact is closed, a stick circuit for said stick relay controlled by said traffic contact independently of said manually controllable contact, and manually 50 controllable means for operating said switch to its normal and reverse positions if said stick relay is energized and if said manually controllable contact is open.

4. In combination, a traffic governing device 55 having two control positions for a given stretch of railway track, a traffic contact controlled by traffic conditions and which is at times opened if a train is approaching said traffic governing device from a given direction, a manually controllable 60 contact, a stick relay, a pickup circuit for said stick relay which can be closed by said manually controllable contact if said traffic contact is closed, a stick circuit for said stick relay controlled by said traffic contact independently of 65 said manually controllable contact, and manually controllable means for operating said traffic governing device to each of said two control positions if said stick relay is energized and if said manually controllable contact is open. 70

5. In combination, a stretch of railway track including a switch, a manually operable switch lever having a normal and a reverse position and having a normal and a reverse contact closed only when said lever is in said normal and reverse 75

- positions respectively as well as having a middle contact closed only when said lever is between its normal and reverse positions, a stick relay, a pickup circuit for said stick relay controlled by 5 said middle contact and by traffic conditions in said stretch of track, a stick circuit for said stick relay controlled by traffic conditions in said stretch of track independently of said lever, an asymmetric unit connected across the winding of 10 said stick relay to permit energy stored in said relay by said pickup circuit to send current through said winding in the same direction as said pickup circuit if said pickup circuit is opened before said stick circuit becomes closed, and means controlled by said normal and reverse contacts and by said stick relay for operating said 15 switch to its normal and reverse positions if said stick relay is energized.
6. In combination, a railway track switch, a manually controllable contact, a traffic contact 20
- closed only by traffic conditions suitable for operation of said switch, a stick relay, a pickup circuit for said stick relay closed by said manually controllable contact if said traffic contact is closed, a stick circuit for said stick relay controlled by said traffic contact independently of said manually controllable contact, an asymmetric unit connected across the winding of said stick relay to permit energy stored in said relay by said pickup circuit to send current through 10 said winding in the same direction as said pickup circuit if said pickup circuit is opened before said stick circuit becomes closed, and manually controllable means for operating said switch to its normal and reverse positions if said stick relay is energized and if said manually controllable contact is open.
